US0D1022832S

(12) **United States Design Patent** (10) **Patent No.:** **US D1,022,832 S**
(45) **Date of Patent:** **** Apr. 16, 2024**

(54) **BODY TRIM COMPONENT FOR MOTOR VEHICLE**

(71) Applicant: **Dr. Ing. h.c. F. Porsche Aktiengesellschaft**, Stuttgart (DE)

(72) Inventor: **Fabian Schmölz**, Stuttgart (DE)

(73) Assignee: **Dr. Ing. h.c. F. Porsche Aktiengesellschaft** (DE)

(**) Term: **15 Years**

(21) Appl. No.: **29/831,617**

(22) Filed: **Mar. 22, 2022**

(30) **Foreign Application Priority Data**

Sep. 30, 2021 (EM) 008712988-0007
Sep. 30, 2021 (EM) 008712988-0008

(57) **CLAIM**

The ornamental design for a body trim component for motor vehicle, as shown and described.

DESCRIPTION

FIG. 1 is a perspective view of a body trim component for motor vehicle according to a first embodiment showing my new design;

FIG. 2 is a front view thereof;

FIG. 3 is a rear view thereof;

FIG. 4 is a right view thereof;

FIG. 5 is a left view thereof;

FIG. 6 is a top view thereof; and

FIG. 7 is a bottom view thereof.

FIG. 8 is a perspective view of a body trim component for motor vehicle according to a second embodiment showing my new design;

FIG. 9 is a front view thereof;

FIG. 10 is a rear view thereof;

(Continued)

FIG. 11 is a left view thereof;
FIG. 12 is a right view thereof;
FIG. 13 is a top view thereof; and,
FIG. 14 is a bottom view thereof.

1 Claim, 14 Drawing Sheets
